COMBINED IRONING BOARD COVER AND
IRON PAD OR PAD HOLDER

Fred Galbraith, New York, N. Y.

Application September 27, 1945, Serial No. 618,943

1 Claim. (Cl. 38—140)

1

This invention relates to new and useful improvements in a combination ironing board cover and iron pad or pad holder.

More particularly, the invention proposes a new and improved combination as stated above which is characterized by the fact that the iron pad or pad holder is mounted upon the board cover. With this arrangement the iron pad is never lost or mislaid. It is always in position and the operator may always place the iron in the same convenient spot and never burn, scorch or injure the cover.

The invention contemplates numerous modified forms which distinguish from each other in the details for mounting the iron pad or pad holder on the board cover.

In certain of the modified forms an arrangement is provided whereby it is possible to support the iron pad in various angular positions on the board cover.

In accordance with this invention the iron pad may be constructed of numerous materials such as asbestos, metal, plastic and other fireproof materials, which protect the cover when the iron is rested on it while the garments are adjusted to the ironing board.

Still further, the invention proposes improved combination cover and pad holder as previously explained which may be sold at a low cost.

For further comprehension of the invention, and of the objects and advantages thereof, reference will be had to the following description and accompanying drawings, and to the appended claim in which the various novel features of the invention are more particularly set forth.

In the accompanying drawing forming a material part of this disclosure:

Fig. 1 is a perspective view of an ironing board having a board cover which is provided with an iron pad holder and pad embodying this invention.

Fig. 2 is a fragmentary enlarged perspective detailed view of a portion of Fig. 1 showing details of the iron pad holder.

Fig. 3 is a fragmentary enlarged vertical sectional view taken on the line 3—3 of Fig. 2.

Fig. 4 is a fragmentary perspective view similar to Fig. 2 but showing another embodiment of this invention.

Fig. 5 is a fragmentary enlarged vertical sectional view taken on the line 5—5 of Fig. 4.

Fig. 6 is another perspective view similar to Fig. 2 but illustrating still another embodiment of this invention.

2

Fig. 7 is a fragmentary enlarged sectional view taken on the line 7—7 of Fig. 6.

Fig. 8 is a fragmentary enlarged vertical sectional view taken on the line 8—8 of Fig. 6.

Fig. 9 is a fragmentary bottom elevational view of the iron pad shown in Figs. 6—8.

Fig. 10 is another perspective view similar to Fig. 2 but illustrating still another embodiment of the invention.

Fig. 11 is a fragmentary view taken on the line 11—11 of Fig. 10.

Fig. 12 is a fragmentary sectional view taken on the line 12—12 of Fig. 10.

The new and improved combination ironing board cover and iron pad holder, in accordance with this invention, includes a cloth casing 15, for covering an ironing board. This casing 15 is associated with means for mounting an iron pad 16 at a convenient position. In that form

20 of the invention shown in Figs. 1—3 inclusive, the holding means for the pad 16 includes a frame 17 of sheet metal, thermo-plastic or other stiff material.

This frame 17 is associated with fastening elements 18 arranged upon one end and two of its sides by which it is mounted in position on the cloth casing 15. The frame 17 has its free end provided with a cloth flap 19 for engaging the edge portion of the iron pad 16 for holding the iron pad in position beneath the frame. This cloth flap 19 is attached to the frame 17 with fastening elements 21. The dot and dash lines 19' in Fig. 2 schematically illustrates the manner in which the flap 19 may be pulled out so as to expose one end of the iron pad 16 which then may be slipped out from beneath the frame 17.

30 The fastening elements 18 normally engage one end and two of the sides of the pad 16 to securely hold it in position. The fastening elements 18 are in the nature of grommets, or other similar fastening devices.

The operation and use of the combination ironing board cover and iron pad holder may be understood from the following:

45 In the normal position of these parts, as illustrated in Fig. 1, the operator irons in the usual way and rests the iron on the pad 16. When it is desired to remove the pad it is merely necessary to pull out the flap 19 and then the pad 16 is free to be slipped out from the end of the frame 17. The pad may be replaced whenever desired.

50 In Figs. 4 and 5, a modified form of the invention has been shown which is similar to the prior form in the fact that the cloth casing 15 for

covering an ironing board is provided with an iron pad 16 which is fixedly mounted thereon. This iron pad 16 is fixedly mounted by a group of clips 24 engaging the four edges thereof. Each clip 24 is in the nature of a hook-like member, preferably formed from sheet metal, or other stiff material. Each clip 24 is held fixedly in position upon the casing 15 with a grommet 25 or rivet, or similar fastening element. Preferably, the clips 24 are pliable so that they may be bent, or flexed open to free the iron pad 16 when this is desire.

In Figs. 6-9 still another form of the invention is shown which is similar to the prior forms in the fact that the cloth casing 15 for an ironing board is provided with an iron pad 16 fixedly mounted thereon. This pad 16 is secured in position by a grommet 28 engaging through one of its corners and through the material of the casing 15. The three remaining corners of the pad 16 are provided with relatively short grommets 29. Pins 30 are soldered to the undersides of the grommets 29 and having split ends with pointed portions 31 directed away from each other. These pointed portions 31 may be engaged into the casing 16.

The pins 30 may be disengaged from the casing 15 whenever desired. Then the pad 16 is free to be pivoted to various inclined positions. One of such positions is indicated by the dot and dash lines 16'. In any angular position the pad 16 may be fixed by engaging the pins 30 into the material of the cloth casing.

In Figs. 10-12 still another embodiment of the invention is shown which is very similar to that form of the invention illustrated in Figs. 1-3. However, this form distinguishes from the prior form in the fact that the frame 17 is pivotally mounted upon the cloth casing 15 by a grommet 34 engaged through one end of the frame 17 and through the material of the casing 15. The frame 17 is provided with relatively short grommets 35 at its sides. Pins 36 are soldered to the undersides of the grommets 25. These pins have bifurcated ends 37 which may be pierced into the casing 15.

In other respects this form of the invention is similar to that previously shown and like reference numerals identify like parts in each of the several views.

The use and operation of this form is substantially identical to the first form disclosed herein, distinguishing merely in the fact that the frame 17 may be pivoted to various angular positions by disengaging the pins 36 and pivoting the frame 17 by using the grommet 34 as a pivot. The pins 36 may then be re-engaged with the casing 15 to hold the frame 17 in its new position. The ironing pad 16 is slipped beneath the frame 17 in the usual way. It is held by the cloth flap 19.

While I have illustrated and described the preferred embodiments of my invention, it is to be understood that I do not limit myself to the precise constructions herein disclosed and the right is reserved to all changes and modifications coming within the scope of the invention as defined in the appended claim.

Having thus described my invention, what I claim as new, and desire to secure by United States Letter Patent, is:

A combination ironing board cover and iron pad, comprising a cloth casing for covering an ironing board, an iron pad disposed on said casing, a grommet engaged through one corner of said pad and said casing for pivotally supporting said pad, additional grommets mounted upon edge portions of said pad, and pins mounted on said additional grommets and engageable with said casing.

FRED GALBRAITH.
